US00D745051S

(12) **United States Design Patent**
Kim et al.

(10) **Patent No.:** **US D745,051 S**
(45) **Date of Patent:** **** Dec. 8, 2015**

(54) **DISPLAY SCREEN OR PORTION THEREOF
WITH ICON**

(71) Applicant: **Samsung Electronics Co., Ltd.,**
Suwon-si (KR)

(72) Inventors: **Min-Sun Kim**, Seongnam-si (KR);
Joon-Il Park, Seoul (KR)

(73) Assignee: **Samsung Electronics Co., Ltd.,**
Suwon-si (KR)

(**) Term: **14 Years**

(21) Appl. No.: **29/467,934**

(22) Filed: **Sep. 25, 2013**

(30) **Foreign Application Priority Data**

May 29, 2013 (KR) 30-2013-0027903

(51) **LOC (10) Cl.** **14-04**

(52) **U.S. Cl.**
USPC **D14/491**

(58) **Field of Classification Search**

USPC D14/485-495

CPC G06F 3/048; G06F 3/04817; G06F 3/0482

(57) **CLAIM**

The ornamental design for a display screen or portion thereof with icon, as shown and described.

DESCRIPTION

FIG. 1 is a front view of a display screen or portion thereof with icon showing my new design; and,

FIG. 2 is a front view of a second embodiment thereof.

The broken lines shown in the drawings illustrate the display screen and form no part of the claimed design.

1 Claim, 2 Drawing Sheets
